INVENTOR.

UNITED STATES PATENT OFFICE.

DWIGHT M. DICKINSON, OF BRIDGEPORT, CONNECTICUT, ASSIGNOR OF
ONE-HALF TO THOMAS J. CARR, OF SAME PLACE.

HELICAL-GRIP PAPER PENCIL.

SPECIFICATION forming part of Letters Patent No. 673,469, dated May 7, 1901.

Application filed September 13, 1900. Serial No. 29,897. (No model.)

To all whom it may concern:

Be it known that I, DWIGHT M. DICKINSON, a citizen of the United States, residing at Bridgeport, county of Fairfield, State of Connecticut, have invented a new and useful 5 Helical-Grip Paper Pencil, of which the following is a specification.

My invention relates to the class of lead pencils in which independent leads are used, 10 and has for its object to provide a pencil of this character which shall be neat and attractive in appearance, light, thoroughly reliable, able to stand hard usage without injury, and, most important of all, which may 15 be produced at a mere fraction of the cost of any pencil of the class now upon the market.

With these ends in view I have devised the novel pencil I will now describe in which the lead is held in place by a helix of paper through 20 which it passes, the helix forming a grip or clutch which holds the lead firmly in place, but which permits it to be readily adjusted or removed and a new one placed in position at the convenience of the operator.

25 In the accompanying drawings, forming part of this specification, Figure 1 is an elevation of my novel pencil complete; Fig. 2, a longitudinal section corresponding therewith; Fig. 3, an elevation of the helical grip 30 and the lead removed; Fig. 4, a plan view of a blank of paper for the helical grip; and Fig. 5 is a cross-section, on a greatly-enlarged scale, of the helical grip and the lead, showing the coating of size upon the lead.

35 A denotes the case; B, a rubber eraser, which may or may not be fixed in one end of the case; C, a lead, and D my novel helical grip.

The case may be made of any suitable material, as metal, wood, rubber, or paper. A 40 very inexpensive and durable case and one susceptible of any desired amount of ornamentation may be made from a strip of paper rolled on a mandrel, the outer coils of the strip being glued or cemented together. If 45 the cases are made from separate blanks of paper, a taper, as at 10, may be formed at the open end of each case by tapering that edge of the blank, the end of the blank that forms the inner coil of the helix being made slightly 50 wider than the other. I have shown the case as made with its inner and outer sides parallel.

It should be understood, however, that this is a matter of no consequence whatever so far as the principle of my invention is concerned. If preferred, the case may be made to taper 55 from either end toward the other, or it may be made of greatest diameter intermediate the ends and may be made of uniform or varying thickness. The lead may of course be of any size, color, or hardness that may be desired. 60 An important feature of my invention, however, is that I cover the leads with a coating of size, which I have indicated by 11 in Fig. 5 and the purpose of which I shall presently more fully explain. 65

12 denotes a washer or plug which may or may not be fixed at the inner end of the lead and may be formed from a roll of paper or in any suitable and inexpensive manner. This washer is adapted to pass freely into the case, 70 and when used acts to hold the inner end of the lead against vibration, so that the pencil may be dropped in use without danger of breaking the lead.

The special shape of the blank of paper 75 from which the helical grip is made is of course not of the essence of my invention, the essential features of which are that the helical grip fit closely enough in the open end of the case so it will remain firmly in position in use, 80 that it have a longitudinal opening 20 large enough to receive the lead extending through it, that the outer portion only of the blank be glued or cemented, so that all the inner portion of the helix will be unsecured, and that 85 the blank be long enough to form a relatively hard, but at the same time thoroughly elastic helix, so that the lead will be gripped firmly thereby. A blank shaped substantially as in Fig. 4 has been found quite satisfactory in 90 practice, as it provides a portion 13, which is adapted to fit closely within the open end of the case, a shoulder 14, which is adapted to rest against the end of the case and serve as a stop to limit the inward movement of the 95 helical grip, as clearly shown in Figs. 1 and 2, and also a taper 15, which runs out on the surface of the lead. In the blank shown it will be noted that the edges are straight, but not parallel, the blank being relatively wide 100 at the end which forms the inner coil of the helix and tapering toward the other end, this

2
taper of the blank forming the taper 15 of the completed helical grip. The shoulder 14 of the completed helical grip is formed by removing a portion of the blank at the end which forms the outer coil of the completed helical grip and on the side opposite the incline. For convenience in illustration I have indicated the inclined edge of the blank in Fig. 4 by 16, the straight edge by 17, the relatively wide end by 18, and the cut-away portion at the opposite end by 19.

15 The operation of my novel pencil is as follows: It should be borne in mind that the leads are covered with a suitable size or varnish—*i. e.*, any solution of gelatinous material, as glue, starch, or rosin, that will glaze the surface and prevent the graphite of the lead from rubbing off upon the inner coil of the helical grip and acting as a lubricant. The effect of 20 the size upon the lead is to produce sufficient friction between the surface of the lead and the inner coil of the helical grip, so that the lead will be held firmly under the ordinary conditions of use. When it is desired to adjust the lead, however—*i. e.*, provide a longer point—the operator removes the helical grip from the case, holds the helical grip with the thumb and finger of one hand, and turns the lead backward with the thumb and finger of 25 the other hand, at the same time pushing it forward as far as may be required, or withdrawing it if required. Having adjusted the lead in the helical grip, it is locked in place with ample firmness for the ordinary conditions of use by giving the lead a slight turn 30 forward, the effect of which is to wind the inner coil or coils of the helical grip tightly about the lead. If for any reason the lead should not adhere with sufficient firmness to 35 the inner coil of the helical grip, the difficulty may be remedied in an instant by removing the lead from the helical grip, wetting it slightly, and again inserting it in the grip, at the same time turning it backward, and 40 then when the lead is at the desired adjustment in the helical grip turning it forward again, when it will be firmly locked in place.

45 Having thus described my invention, I claim—

50 1. In a pencil of the character described the combination with a case, of a lead and a holding device for the lead, said holding device being separate from the case and consisting of a helix of paper by which the lead is gripped and which is itself adapted to engage the case.

55 2. A grip for pencil-leads consisting of a helix of paper having a central opening to receive a lead, its inner coils loose and its outer coils secured together, and having a stop portion to engage a case to prevent longitudinal movement therein, substantially as shown, for the purpose specified.

3. A grip for pencil-leads consisting of a helix of paper having a central opening to receive a lead, its inner coils loose, its outer coils secured together and a shoulder 14, substantially as shown, for the purpose specified.

4. A grip for pencil-leads consisting of a helix of paper having a central opening to receive a lead, its inner coils loose, its outer coils secured together and a taper 15 at one end, and a reduced portion at the other end to fit within a case, substantially as shown, for the purpose specified.

5. A grip for pencil-leads consisting of a helix of paper formed from a blank having an inclined edge, a straight edge, a relatively wide end and a cut-away portion at the opposite end, substantially as shown, for the purpose specified.

6. The combination with a case and a lead having its surface covered with size, of a grip for the lead consisting of a helix of paper through which the lead is passed, the inner coils of the helix being unsecured and the outer coils being secured together, and having a stop portion to engage the end of said case.

7. The combination with a case and a lead, of a grip for the lead consisting of a helix of paper through which the lead is passed, said grip having a shoulder adapted to engage the end of the case to limit the inward movement of the grip.

8. The combination with a case and a lead having a washer upon its inner end which is adapted to pass loosely within the case for the purpose set forth, of a grip for the lead consisting of a helix of paper which holds the lead and itself engages the case, said grip having a shoulder to engage the end of the case to limit inward movement of the grip and lead.

80 In testimony whereof I affix my signature in presence of two witnesses.

DWIGHT M. DICKINSON.
